APPARATUS FOR STIRRING MOLTEN METAL

Frederick R. Muller, Carteret, and Walter T. Monson, Newark, N. J., assignors to The American Metal Company, Limited, New York, N. Y., a corporation of New York

Application March 2, 1939, Serial No. 259,424

4 Claims. (Cl. 266—34)

This invention relates to apparatus for stirring molten metal.

In various processes for treating molten metal, such for example as the rapid detinning of lead, it is necessary to provide apparatus for stirring large masses of the molten metal. The temperature of the molten metal may range up to 1200° F. in the case of processes for detinning molten lead. For the stirring apparatus impellers rotating at speeds up to 1800 R. P. M. may be used. Considering the weight of the molten metal and the inertia of the circulating streams thereof, it has heretofore been found very difficult to provide a durable and rugged stirring unit which will withstand these severe conditions. One of the serious difficulties resides in the provision of suitable means for supporting the rapidly rotating stirring unit in the presence of the heavy moving masses of molten metal in such manner that certain vibrations will not become so serious as to quickly destroy the rotating parts and the supports therefor. That is, if an impeller is mounted on a shaft extending down into the molten metal, it is difficult to provide a bearing for the lower portion of the shaft which will withstand the conditions present. Accordingly it has been attempted to support the shaft by providing the journals or bearings therefor at its upper end or above the molten metal. But this practice leaves the lower end of the shaft relatively free to bend or vibrate in radial directions, thereby permitting, at high speeds, a whipping action at the lower end of the shaft which seriously increases the wear and tear on all of the rotating parts and bearings, necessitating replacement of parts within a few days.

The objects of the present invention therefore include the provision of means for stabilizing the rotating parts of stirring apparatus of the character above referred to. Various further and more specific objects, features and advantages will clearly appear from the detailed description given below taken in connection with the accompanying drawing which forms a part of this specification and illustrates merely by way of example a preferred form of the apparatus of the invention. The invention consists in such novel features, arrangements and combinations of parts as may be shown and described in connection with the apparatus herein disclosed by way of example.

In the drawing, Fig. 1 is a vertical sectional view showing a kettle of molten metal in connection with which stirring apparatus in accordance with this invention is mounted.

Fig. 2 is an enlarged elevational view showing an impeller for stirring molten metal mounted upon the lower end of a rotatable shaft to which a stabilizing device is applied in accordance with this invention;

Fig. 3 is a vertical sectional view showing in further detail the parts above referred to in connection with Fig. 2;

Fig. 4 is a bottom view of the parts shown in Fig. 2; and

Fig. 5 is a perspective view of a stabilizing device in accordance with this invention, shown detached from the other rotatable parts of the stirring apparatus.

Referring now to Fig. 1, a kettle is indicated at 10 containing a body of molten metal 11 comprising for example, molten lead, which is being subjected to a process involving rapid stirring. A mass of dross which is separated from the molten metal is indicated at 12. The kettle may be mounted as shown in a suitable fire box and heated by oil or gas flames as at 13.

At the top of the kettle a suitable frame work may be provided as at 14 for supporting a motor 15 having its shaft detachably coupled as at 16 with a shaft 17. The shaft 17 may extend downwardly into the molten metal and the greater portion of the shaft may be covered and protected as by a sleeve 18 against deterioration in the presence of the high temperature metal, and 30 against abrasion due to the presence of the dross. Suitable bearing or journal means may be provided, water-cooled if desired, as at 19' on the frame work 14.

At the lower end of the shaft a rotatable impeller as at 19 may be fixed as by key 20 and set screw 21. The impeller of the form shown is so shaped that upon rapid turning of the shaft by the motor, the molten metal will be caused to rapidly circulate in paths such as indicated generally by the arrows in Fig. 1.

Heretofore with impellers thus mounted on the lower end of a vertically extended shaft rotating at high speed in molten metal, the currents of the molten metal have been such as to soon set up progressively increasing and powerful whipping effects at the impeller, i. e., vibrations of the lower end of the shaft radially and about the axis, with the result that the shaft may soon become bent and jam, the bearings therefor are destroyed, and all rotating parts are subjected to excessive wear. The difficulty of providing any dependable bearing means at the lower end of the shaft capable of withstanding the conditions present, will be quite apparent.

It has been found, however, that the lower end of such a shaft may be stabilized to a surprising degree against such whipping effects by providing a coaxial extension for the lower end of the shaft, as for example in the form of a cylinder as indicated at 22. The cylinder 22 is preferably, although not in all cases necessarily, made hollow as shown. With a hollow cylinder the results are considerably improved over the results obtained with a solid cylinder. This cylinder may be attached to the lower end of the shaft as by means of a collar 23, the collar in turn having a keyway 24 for receiving the lower end of the above-mentioned key 20. The cylinder and collar may be secured in respect to the shaft and key as by a set screw 24.

Although we have not precisely determined in all respects the manner in which this cylindrical extension operates so effectively in stabilizing the lower end of the shaft, it is believed that there may be a number of factors involved. Thus it will be noted that this extension presents an extended surface of revolution providing a bearing surface against the surrounding stream or streams of molten metal as drawn upwardly into the impeller. That is, above the impeller there will be a downwardly flowing movement of molten metal toward the impeller; the vortex created by the stirrer being more or less filled with dross as indicated. Beneath the impeller the movement of lead is symmetrical about the shaft axis, whereby the cylinder 22 has forces exerted upon it equally from all directions and as a result it exerts a stabilizing force on the shaft. In view of the inertia of the heavy moving streams, the cylindrical member may therefore act somewhat as a bearing despite the absence of any fixed journal. Also the cylindrical member, if made hollow as preferred, will contain a substantial mass of the heavy molten metal, which in the case of lead will cause the extension to have a considerable inertia, that is, much greater than if the cylinder were of solid iron or steel. This may tend to dampen the vibrations and whipping effect. Also the rising and swirling current of heavy molten metal which engages and enters into and also surrounds this cylindrical member, may be so modified by the presence of this member as to tend to check or neutralize forces causing wobbling or whipping of the impeller. Also a swirling current of the molten metal may to some extent be established within the lower open end of the cylinder and out of phase with the swirling current outside, in such manner as to tend to neutralize the whipping action. In addition to all these effects the static head of lead (which as a solid, has a specific gravity of 11.37) exerts a stabilizing pressure on the extension.

With an impeller of the type shown in the drawing and having a diameter of from 9 to 12 inches and mounted about 2½ feet below the bearing on a 2¼ inch shaft, it has been found that the cylindrical member 22 will give a surprisingly effective stabilizing effect if made in the neighborhood of 4 to 6 inches in diameter and 10 to 12 inches long. However, these dimensions are given simply as illustrative of a preferred example and it is to be understood that the invention as hereinafter claimed is not to be limited thereto. The cylinder may for example be made of a section of relatively rigid machined steel tubing, preferably for best results, somewhat larger in diameter than the impeller shaft.

The effectiveness of the invention may be appreciated from the fact that with a typical high

speed installation before applying the above described stabilizing device, the shaft, other rotating parts or bearing, often had to be replaced after about three days of operation. On the other hand, with the application of the above described stabilizing means, mechanical difficulties were substantially eliminated and the apparatus was made capable of substantially continuous operation for a number of months without repair or replacement of parts.

While the invention has been described in detail with respect to a particular preferred example, it will be understood by those skilled in the art after understanding the invention that various changes and modifications may be made without departing from the spirit and scope of the invention, and it is intended therefore in the appended claims to cover all such changes and modifications.

What is claimed as new and desired to be secured by Letters Patent is:

1. In apparatus for stirring molten metal, a rotatable shaft for extending downwardly for a substantial distance into the molten metal, journal means for said shaft, the journal means being located above the molten metal, an impeller within the molten metal and fixed to said shaft, said impeller being so shaped as to cause molten metal to be drawn upwardly to the impeller and thence outwardly therefrom, the end of the shaft within the molten metal being unsupported by any bearing structure, means at the upper end of the shaft for rotating same at speeds such that the lower portion of the shaft is subjected to forces tending to cause destructive transverse vibration and bending thereof, and means on said shaft below said impeller for stabilizing the lower portion of the shaft against such vibration and bending, said means comprising an enlarged coaxial extension for the lower end of the shaft, formed with a surface of revolution extending to a substantial distance below the impeller and presenting extended bearing areas against the surrounding stream of molten metal as drawn upwardly to the impeller.

2. In apparatus for stirring molten metal, a rotatable shaft having a free end extending downwardly for a substantial distance into the molten metal, an impeller within the molten metal and fixed to said shaft, means at the upper end of the shaft for rotating same at speeds such that the lower portion of the shaft is subjected to forces tending to cause destructive transverse vibration and bending thereof, and means on said shaft below said impeller for stabilizing the lower portion of the shaft and impeller against such vibration or bending, said means comprising a coaxial extension for the lower end of the shaft, formed with a surface of revolution extending to a substantial distance below the impeller and presenting an extended bearing surface against the surrounding streams of molten metal.

3. In apparatus for stirring molten metal, a rotatable shaft having a free end extending downwardly for a substantial distance into the molten metal, an impeller within the molten metal and fixed to said shaft, and means on said shaft below said impeller for stabilizing the lower portion of the shaft and impeller against radial vibration, said means comprising a coaxial extension fixed to the lower end of the shaft, such extension being a hollow cylinder open at its lower end.

4. In apparatus for stirring molten metal, a rotatable shaft having a free end extending down-

wardly for a substantial distance into the molten metal, an impeller within the molten metal and fixed to said shaft, and means on said shaft below said impeller for stabilizing the lower portion of the shaft and impeller against radial vibration, said means comprising a coaxial extension for

the lower end of the shaft, formed with external and internal surfaces of revolution, both of said surfaces contacting with the molten metal.
